(57) **CLAIM**

The ornamental design for an aft bulkhead, as shown and described.

DESCRIPTION

FIG. 1 is a perspective view of the aft bulkhead showing our new design;

FIG. 2 is a front view of the aft bulkhead of FIG. 1;

FIG. 3 is a back view of the aft bulkhead of FIG. 1;

FIG. 4 is a right view of the aft bulkhead of FIG. 1;

FIG. 5 is a left view of the aft bulkhead of FIG. 1;

FIG. 6 is a top view of the aft bulkhead of FIG. 1;

FIG. 7 is a bottom view of the aft bulkhead of FIG. 1; and,

FIG. 8 is a perspective view of the aft bulkhead of FIG. 1 shown with the environment removed for clarity of disclosure.

In FIGS. 1-8, broken lines indicate environmental structure that forms no part of the claimed design. The dot-dash broken lines shown in FIGS. 1, 2 and 8 depict portions of the aft bulkhead that form no part of the claimed design.
